UNITED STATES PATENT OFFICE

CHARLES G. CLEMENT, OF EDGERTON, WISCONSIN, ASSIGNOR TO HIGHWAY TRAILER COMPANY, OF EDGERTON, WISCONSIN, A CORPORATION OF WISCONSIN

SLIDING COVER FOR DUMPING BODIES

Application filed August 28, 1926. Serial No. 132,054.

This invention relates to vehicle bodies of the hopper type in which the body is mounted for tilting, as by a rolling movement upon a main frame of the vehicle for the purpose of dumping its contents. One object of the invention is to provide covering means for such a body, adapted to be opened at will and mounted independently of the body itself so as not to alter the center of gravity of said body, or interfere with the dumping action. Another object is to provide such a cover in a form which may be raised or lowered without extending laterally beyond the normal width of the body itself. The invention consists in certain features and elements of construction in combination as herein described and shown in the drawings, as indicated by the claims.

In the drawings:

20 Figure 1 is an end elevation of the body and a portion of the vehicle frame, the latter being shown partly in section.

Figure 2 is a detail side elevation of one of the covers and operating mechanism therefor.

25 Figure 3 is a fragmental detail showing a corner of the body in end elevation with the cover in raised position.

Figure 4 is a detail section on an enlarged scale, and taken as indicated at line 4—4, on 30 Figure 2.

Figure 5 is a detail section taken as indicated at line 5—5, on Figure 2.

For the purposes of illustration this invention may be understood as shown in connection with a trailer vehicle having supporting wheels, 1, axles, 2, and a drop frame, including the lower longitudinal channels, 3, and upper channels 4, the latter forming the frame members adjacent the ends of the hopper body, 5. The lower channels, 3, support cross rails, 6, and the hopper, 5, is provided with curved rockers, 7, adapted to roll on the rails, 6, for tilting the hopper to discharge its contents at either side of the vehicle. This type of construction is more fully illustrated in my co-pending application, Serial No. 46,730, filed July 29th, 1925.

At each end of the vehicle frame there is mounted on the members, 4, an upstanding A-frame, 8, and these A-frames are tied to-

gether by a longitudinal frame member such as the pipe or tube, 9, which carries laterally extending bracket arms, 9^a, serving to support hinge connections for the covers, which are the subject of this invention. One or more of these covers may be provided at each side of the body, depending on the length of the hopper, 5, but for a hopper of average size I prefer to supply two covers at each side. Each cover consists of an upper section, 10, and a lower section, 11, the latter being slidably associated with the former. The upper section, 10, consists of a sheet metal plate having its end portions attached to arms, 12, 12, and said arms are loosely mounted on a shaft, 13, journaled in the ends of the bracket arms, 9^a, which extend laterally from the central frame tube, 9, as seen in Figures 2 and 5. One end of the shaft, 13, projects beyond the vertical plane of the A-frame, 8, and carries a sprocket wheel, 14, connected by a chain, 15, with a second sprocket, 16, on the shaft, 17, of a worm wheel, 18, mounted at a lower point on the A-frame in operative relation to a worm whose shaft, 19, is provided with a hand crank, 20. By means of the crank, 20, the shaft, 13, may be rotated at will for swinging up or down the arms, 21, which are rigidly secured to the shaft adjacent to the arms, 12. Said arms, 21, are connected by links, 22, to points on the cover section, 11, near its lower edge, and said section, 11, is slidably engaged in the arms, 12, so that the first effect of the rotation of the shaft, 13, in a direction to swing the arms, 21, upward is to draw the section, 11, upwardly over the section, 10, of the cover. As shown in Figure 4, the arms, 12, are in the form of channels opening toward the ends of the cover plates, 10 and 11, and the plate, 11, is reinforced at its ends by angle members, 23, which occupy the available space in the channels, 12, with sufficient clearance to allow of easy sliding movement of the cover section, 11, therein. The plate, 11, is further reinforced by angles, 24 and 25, at its upper and lower edges, respectively, and the links, 22, are secured to the plate, 11, by any convenient form of lug, 26, in which their pivots, 27, may be mounted. The lower edge of the cover plate, 10, may be reinforced by 100

a downwardly directed angle, 28, so that its upper surface is unobstructed in order to permit the lower plate, 11, to slide smoothly over it.

5 When the upward movement of the arms, 21, has carried the plate, 11, to the upper ends of the channels, 12, or to any stop therein which may arrest further movement, the continued rotation of the shaft, 13, will act to 10 swing the arms, 12, about the axis of the shaft, carrying with them both cover plates, 10 and 11, and thus opening the upper half of the cover to any extent desired. This action is illustrated in Figure 3.

15 This arrangement insures that before any of the covers is swung upwardly from its inclined position in which it closes the hopper, 5, the effective length of the cover is diminished by the sliding or telescopic movement 20 of the lower section, 11, with respect to the section, 10, so that when the cover is finally rotated it does not project laterally beyond the side of the hopper body, 5. This eliminates the danger of striking the upraised 25 cover against buildings or telephone poles as the vehicle moves along a street or alley, as for example when used for the collection of ashes or garbage. It also keeps the center of gravity of the covers themselves fairly low, 30 even in their upraised position, so that the stability of the vehicle is not affected. And, of course, the independent support of the covers upon the A-frames, 8, and their connecting member, 9, permits the hopper body, 35 5, to be rolled over on its side in exactly the same manner in which it would be tilted if there were no covers; it being understood, also, that the covers at one side are raised at least to the point indicated in Figure 3, to 40 allow for this rolling movement of the body. For operating the covers I prefer to employ a worm wheel, as at 18, because the worm gearing serves to lock the mechanism in any position in which it is left, without the 45 vision of other locking devices.

For completing the enclosure of the material in the hopper body, 5, the end walls of the body are constructed with upright portions, 30, extending higher than the lateral 50 margins so as to meet the inclined planes of the covers. In the space between the upper edges of the cover sections, 10, I provide a fixed cover plate, 31, which may be supported from the under sides of the bracket arms, 9^a, 55 just below the frame tube, 9, as seen in Figure 5. The end walls, 30, cannot extend quite up to the plate, 31, without interfering with the tilting movement of the hopper, 5, but the gap may be covered by a depending skirt portion, 32, at each end of the vehicle, which laps over the wall, 30, in a plane parallel to that in which it moves when the body is tilted.

I claim:—

1. In combination with a hopper body, a 65 cover comprising a section hingedly mount-

ed adjacent the middle of the body and extending part-way toward the side thereof, with a supplemental section slidably on the first and dimensioned to extend therefrom to the side of the body, together with operating 70 means for raising the cover, adapted for sliding said supplemental section toward the hinged mounting of the other section in the initial portion of the opening movement.

2. In combination with a hopper body, a 75 rock shaft extending over the body adjacent the middle portion, with arms loose on said shaft and extending toward the side of the body, a cover section fixed to said arms and a supplemental section slidably guided by 80 said arms for movement toward and from the side of the body in a plane substantially parallel to that of the first section, and means operable by the rotation of said shaft for sliding one section in said arms and swinging the other section with said arms about the axis of said shaft.

3. In combination with a hopper body, a 85 rock shaft mounted over the body and a cover extending from said rock shaft to the side of the body, said cover comprising a section hingedly connected to the rock shaft and a supplemental section slidable over the first for extension therefrom to the side of the body, a lever arm fixed to the rock shaft and 90 extending over the hinged section with a link connecting the outer end of said arm with the slidable section, whereby rotation of the shaft first draws said slidable section over the other toward the rock shaft and then 95 swings both sections together upwardly about the shaft as an axis.

4. In the combination defined in claim 3, operating gearing for said rock shaft which includes drive connections adapted to turn the shaft positively in either direction for 105 opening or closing the cover at will.

5. In combination with a hopper body, a 110 cover comprising a section hingedly mounted for opening upwardly, a section slidable over the first in a plane parallel thereto, means supporting the hinged mounting independently of the body, said hinged mounting and support including a rock shaft extending 115 above the body, means on the hinged cover section loosely engaging said rock shaft with journaling means for the shaft mounted on said supporting means, and linkage between the shaft and the slidable section whereby the latter is drawn toward the shaft axis in the initial portion of the opening movement of the cover when the shaft is rotated, together with operating means for said shaft carried by said supporting means below the level of the shaft.

6. In combination with a hopper body, 120 upright supports adjacent each end of the body, a pair of rock shafts extending longitudinally over the middle portion of the body, a fixed cover section carried by the uprights 125 130

and bridging the space between the rock shafts, together with covers hingedly attached to said rock shafts and sloping downwardly toward opposite sides of the body respectively, each cover comprising a slidably extensible section dimensioned to reach the side of the body when extended, an operating arm on each rock shaft linked to one of said extensions, and means for rotating said shafts independently of each other.

7. In combination with a hopper body, uprights at opposite ends of the body respectively, a longitudinal frame member connecting said uprights above the body, journal brackets associated with the uprights and a journal bracket carried by said longitudinal member intermediate its ends with four rock shafts aligned in pairs and extending along parallel axes, and journaled in said brackets, covers for the body hinged to said rock shafts respectively, each cover comprising a slidably extensible portion adapted when extended to reach one side of the body, said covers sloping downwardly from the rock shafts in opposite directions at opposite sides of the longitudinal member, a connection from each of the extensible cover portions to its rock shaft, and separate operating means for each of the rock shafts supported on the uprights.

8. In the combination defined in claim 7, said covers and the supporting means therefor being carried independently of the body.

9. In the combination defined in claim 7, each of said separate operating means including manual actuating means supported by the upright at a lower portion thereof.

10. In the construction defined in claim 7, said pairs of rock shafts being transversely spaced; together with a plate registering with the opening between said shafts and secured to said journal brackets.

CHARLES G. CLEMENT.
